(57) **CLAIM**

The ornamental design for a shoe sole, as shown and described.

DESCRIPTION

1. Shoe sole
- 1.1 : Perspective
- 1.2 : Front
- 1.3 : Back
- 1.4 : Right
- 1.5 : Left
- 1.6 : Top
- 1.7 : Bottom

The shoe sole reproduced in design no. 1 corresponds to the left foot; the reproductions of the shoe sole of the right foot are omitted because they are symmetrical to the sole of the left shoe.
